(57) **CLAIM**

The ornamental design for an accessory for electronic device, as shown and described.

DESCRIPTION

FIG. 1 is a front, top and side perspective view of an accessory for electronic device showing the new design; FIG. 2 is an exploded view thereof;

FIG. 3 is a front elevation view of the accessory for electronic device as shown in FIG. 1;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom view thereof;

FIG. 9 is a front, top and side perspective view of piece 1 of the accessory for electronic device of FIG. 1, shown separately to show aspects of the design that are not visible when combined;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom view thereof;

FIG. 16 is a front, top and side perspective view of piece 2 of the accessory for electronic device of FIG. 1, shown separately to show aspects of the design that are not visible when combined;

FIG. 17 is a front elevation view thereof;

FIG. 18 is a rear elevation view thereof;

FIG. 19 is a left side elevation view thereof;

FIG. 20 is a right side elevation view thereof;

FIG. 21 is a top plan view thereof;

(Continued)

FIG. 22 is a bottom view thereof;
 FIG. 23 is an exploded view thereof;
 FIG. 24 is a front elevation view thereof;
 FIG. 25 is a rear elevation view thereof;
 FIG. 26 is a left side elevation view thereof;
 FIG. 27 is a right side elevation view thereof;
 FIG. 28 is a top plan view thereof;
 FIG. 29 is a bottom view thereof; and,
 FIG. 30 is an enlarged view thereof.
